The ornamental design for a spray cap for aerosol containers, as shown and described.

DESCRIPTION

FIG. 1 is an enlarged perspective view of the spray cap for aerosol containers showing the new design;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.

The broken lines are shown for the purpose of illustrating parts of the article that form no part of the claimed design.
